Albert Eink

UNITED STATES PATENT OFFICE

ALBERT EISELE, OF BERLIN-WESTEND, GERMANY

SPEEDOMETER

Application filed April 17, 1930, Serial No. 445,093, and in Germany April 28, 1929.

The improvement consists in novel means for adjusting the tachometer by diverting the path of the flux of the magnetic field by means of a shunt.

- 5 The main feature of the invention resides in the arrangement of lamels or of a iris-shaped diaphragm adapted to form a shunt magnetic field to the main field of the rotating magnets. The lamels are arranged above and 10 coaxially with the rotating magnets and can be radially adjusted with respect to the axis of rotation in order to divert more or less of the magnetic lines of force of the magnets. Accordingly the magnets exert a greater or 15 minor torque on the indicating armature.

A further feature of the invention resides in means arranged outside of the speedometers allowing to easily adjust the shunt magnetic field even while speedometer is working.

20 Other features of the invention will be apparent from the following description.

In the drawing, Fig. 1 is a vertical sectional elevation of the new speedometer, and Fig. 2 is a plan view of the speedometer with the dial plate removed, and Fig. 3 is a plan view of the speedometer with the dial plate in place. Fig. 4 is a cross-section on the line 4-4 of Fig. 2.

30 The C-shaped magnet 2 is rotated by the driving shaft 1. Between the cylindrical poles of the magnet there is arranged the coaxial cylindrical core 2' of soft iron rotating with the magnet. By this arrangement an annular air gap is formed which is penetrated 35 by magnetic lines of force and into which enters the shell of the indicating armature 3 preferably consisting of aluminium.

In the armature 3 the shaft 4 of which is so journaled as to easily rotate, eddy currents are produced by the rotating magnetic field; the armature is thus subjected to the action of said field whereby it is displaced from its initial or zero position in which it is restrained by the force of the spring 5. The 45 angle of deflection is a measure of the velocity of revolution of the magnet 2, and this velocity is shown by the position of the pointer 6.

The iris diaphragm is arranged above the armature 3 as a magnetic shunt parallel to the magnetic field cutting the armature. The

iris diaphragm consists of the solid mounting 7, the adjustable ring 8 and the lamels 9 of a good conductor of magnetism. The latter move radially when the ring 8 is turned. The more the lamels 9 are turned inwards, 55 the more lines of force will be diverted by them into the shunt, and the less will be the strength of the magnetic field in the armature gap, i. e. the less will be the strength of the torque exerted on the armature 3. The 60 dotted line 10 in Fig. 2 indicates the inner position of the lamels. The lamels are suitably insulated against each other for example by coating them with a layer of lacquer in order to diminish the formation of eddy 65 currents in the diaphragm.

In Figure 4 one lamel designated by the numeral 9' has been shown in Fig. 2 partly in full lines and partly in dotted lines. The lamel has on its lower surface a pivot 1' rotatable in the mounting 7. On the upper surface it has a pin 18 engaging into a slot 19 of the rotatable ring 8. The straight line connecting the centres of the pivot and the pin forms with the slot 19 an acute angle so that 75 by turning the ring 8 the lamel is swung inward or outward on its pivot 17.

The diaphragm is comparatively thin and can be additionally mounted into existing 80 complete instruments.

The described arrangement is in particular advantageous for tachometers which are mounted on vehicles running on rails. It is well known that the rims wear out and the diameters of the wheels are hence decreased. 85 But the indication of the tachometer depends on the effective diameter of the wheel the axle of which drives the instrument. It is now easily possible at any time to adjust the tachometer even while it is working to bring it in 90 accordance with the real diameter of the wheel.

The rotatable ring 8 is provided with a segment of a toothed wheel 11 meshing with the gear 12, the axle 13 of which protrudes to the outside of the instrument. A pointer 14 connected with the ring 8 is led through a slot of the dial plate 15 and marks the position of the diaphragm on a special graduation made according to the diameters of the wheels. 100

If therefore a certain diameter of a wheel is known the knob 16 is to be turned till the pointer 14 reaches the corresponding indication.

5 The common method of adjusting the tachometers according to a middle diameter of the wheel may therefore be replaced by the exact gauging according to the real diameter.

What I claim is:

0 1. In a speedometer, a rotating magnet, an armature rotatable about the same axis as the magnet and forming the speed indicating member, a plurality of radially adjustable members of a good conductor of magnetism arranged coaxially with and above the rotating magnet and the armature, and adapted to divert a part of the lines of force out of the magnetic field cutting the armature, and means accessible outside of the speedometer, 5 for operating the said adjustable members.

2. In a speedometer, a rotating magnet, an armature rotatable about the same axis as the magnet and forming the speed indicating member, a plurality of radially adjustable 5 members of a good conductor of magnetism arranged coaxially with and above the rotating magnet and the armature and adapted to divert a part of the lines of force out of the magnetic field cutting the armature, means 10 accessible outside of the speedometer for operating the said adjustable members, and means indicating the adjusted position of the latter members.

In testimony whereof I affix my signature.
15 ALBERT EISELE.
